QUATERNARY AMMONIUM GERMICIDE
COMPOSITIONS

Richard D. Stayner, Albany, Calif., assignor to
California Research Corporation, San Francisco, Calif., a corporation of Delaware

Application September 5, 1950, Serial No. 183,278

3 Claims. (Cl. 167—25)

1

This invention relates to new and improved compositions for the control of microorganisms such as bacteria, fungi, algae, protozoa, and the like. More particularly, the invention relates to compositions which comprise a quaternary ammonium germicide and a promoter.

Prior to my invention, quaternary ammonium compounds, per se, have been used as germicides, etc. The activity of these compounds varies widely with the different types of organic cation radicals contained therein. As a consequence, a great amount of experimental effort and expense has been necessary to develop more efficient types of materials. Such quaternary ammonium compounds are usually costly and, in many cases, are characterized by poor efficiency in the control of microorganisms, particularly spore-forming bacteria, fungi, molds, and the like.

It is an object of my invention to provide novel quaternary ammonium compositions which are economical to produce and more efficient than the quaternary ammonium compounds themselves as germicides, particularly toward spore-forming bacteria, fungi, molds, and the like.

Other objects and advantages of my invention will be apparent from the disclosure which hereinafter appears.

I have found that a quaternary ammonium germicide and pine oil may be combined in such proportions as to produce strongly germicidal compositions having germicidal activity exceeding that of the quaternary ammonium compounds themselves. This resultant improvement in efficiency is highly unexpected since pine oil is of itself a relatively poor germicide, particularly toward spore-forming bacteria, fungi, etc., against which even quaternaries are relatively ineffective.

The production of these novel and more highly effective germicidal compositions according to my invention requires only the simplest of procedures. It involves none of the complicated experimentation that is necessary when improvement of the germicidal efficiency of a quaternary ammonium compound is attempted through modification of the hydrophobic cationic portion of the molecule.

The extraordinary effect of my discovery is illustrated graphically by the curve shown in the accompanying drawing. Upon reference to this curve, it will be seen that when certain substantial amounts of a quaternary ammonium compound are combined with pine oil, the resultant composition possesses germicidal activity against a representative fungus such as *T. rosaceum* far in excess of the quaternary alone. On the other

hand, when only small amounts such as about 5% of quaternary ammonium compounds are added to pine oil as would customarily be done to improve the low germicidal efficiency of the pine oil and to impart surface-active properties to it, just a moderate increase in the overall germicidal activity above that of pine oil alone is obtained. This is only as expected since the germicidal activity of the quaternary is recognizably stronger than that of the pine oil. The terms "germicide" and "germicidal" as contemplated herein refer to that class of agents which destroys microorganisms such as bacteria, fungi, algae, protozoa, etc., as well as the effect.

The quaternary ammonium germicides used in the compositions of my invention can be any of several various types which fall within the generic term. These compounds are generally characterized by the formula

wherein at least one of the radicals R₁, R₂, R₃ and R₄ attached to nitrogen atom is a hydrophobic aliphatic, unsaturated aliphatic, cycloaliphatic, araliphatic or aliphaticaryl radical of from 6 to 26 carbon atoms. The hydrophobic radicals, more specifically, may be long-chain alkyl, long-chain alkoxyaryl, long-chain alkylaryl, halogen substituted long-chain alkylaryl, long-chain alkylphenoxyalkyl, arylalkyl, etc., in nature. The remaining radicals on the nitrogen atom other than the preceding hydrophobic radicals may be substituents of hydrocarbon structure ordinarily containing a total of no more than about 12 carbon atoms. Various compounds of these types are more fully illustrated in the disclosure which follows. Mixtures of the different quaternaries may be used in my compositions as well as the single compounds.

The proportions of the quaternary ammonium germicide and the pine oil are critical to my invention. However, these critical proportions may vary over a wide range from a minimum amount of pine oil just sufficient to promote the germicidal activity of the quaternary ammonium compound up to a maximum amount of about 70%. A very marked improvement is obtained with proportions of pine oil ranging from about 10 to about 60% while compositions containing pine oil in proportions of about 20 to about 50% exhibit the greatest increase in germicidal activity.

The improved quaternary ammonium germicide compositions of my invention are prepared

by adding pine oil to the quaternary ammonium compounds in suitable proportions and mixing them together. Various means for mixing and handling the materials will be obvious to persons skilled in the art from this disclosure and, as such, are contemplated by my invention.

As more specific examples of the different types of quaternary ammonium germicides in the novel compositions according to my invention as well as various compounds included in them, I can use the alkyl ammonium halides, such as cetyl trimethyl ammonium bromide, dioctadecyl dimethyl ammonium chloride, etc.; the alkyl aryl ammonium halides, as illustrated by octadecyl dimethyl benzyl ammonium chloride; N-alkyl pyridinium halides, such as N-laurylpyridinium chloride; quaternary ammonium salts containing ether linkages in the molecule, such as parateriary octylphenoxyethoxyethyl dimethyl benzyl ammonium chloride; quaternary ammonium compounds having oxygen in the form of amide or ester linkages as illustrated by N-(laurylcolaminoformylmethyl)-pyridinium chloride; quaternary ammonium compounds containing a sulfonamide group, such as 2-phenyl-3-p-sulfamido-phenyl-5-undecyltetraazolium chloride; as well as quaternary ammonium germicides characterized by a substituted aromatic nucleus such as lauryloxyphenyl trimethyl ammonium chloride, dodecylbenzyl trimethyl ammonium chloride, chlorinated dodecylbenzyl trimethyl ammonium chloride, dodecylphenyl trimethyl ammonium methosulfate, and the like.

Although any of the above types of quaternary ammonium germicide is ordinarily satisfactory in my novel compositions, those which are particularly effective are the long-chain alkyl dimethyl benzyl quaternary ammonium salts, the alkyl-phenoxyalkoxyalkyl dimethyl benzyl quaternary ammonium salts, the N-(acylcolaminoformylmethyl)-pyridinium salts, the long-chain alkyl trimethyl ammonium salts, as well as the long-chain alkylarylmethyl quaternary ammonium compounds.

The long-chain alkylarylmethyl quaternary ammonium germicides which are particularly adapted to the novel compositions of my invention belong to the class of quaternary ammonium salts characterized by the type formula

where R_1 is an alkyl group of 8 to 18 carbon atoms, Ar is an aryl hydrocarbon nucleus, R' is hydrogen or a methyl radical, m is from 1 to 4, Y is a hydrogen or a halogen, n is from 1 to 8, R_2 , R_3 and R_4 are substituents of hydrocarbon structure containing a maximum total of 12 carbon atoms, and X is a salt-forming anionic radical which may be the same as Y .

In the above alkylarylmethyl quaternary ammonium germicides the long-chain alkyl radical R_1 can be any alkyl group of from 8 to 18 carbon atoms. When the alkyl radicals are of a straight chain nature, those containing as few as 8 to 10 carbon atoms are found to be very satisfactory, but when branched chain structures predominate in the acyclic radical, the most satisfactory groups are those containing from 10 to 18 carbon atoms. Suitable alkyl radicals can be obtained from various sources such as the long-chain olefins of 8 to 18 carbon atoms derived from cracked olefinic petroleum fractions or from Fischer-Tropsch synthesis. A preferred source of

long acyclic alkyl radicals is the class of acyclic propylene polymers having from 9 to 15 carbon atoms per molecule, with those having from 12 to 15 carbon atoms being still more preferred.

The aryl nuclei of the long-chain alkylarylmethyl quaternary germicides represented by the above formulae can be benzene, toluene, xylene, naphthalene, anthracene, etc., with benzene and toluene being preferred.

The N-substituted alkyl radicals of the long-chain alkylarylmethyl quaternary ammonium compounds of this invention as already stated should contain no more than 12 carbon atoms, and preferably from 3 to 10 carbon atoms. The hydrocarbon substituents may be separate alkyl radicals attached to the nitrogen atom or they may be combined alkyl and cycloaliphatic hydrocarbon substituents as in the case of N-ethyl piperidine. The hydrocarbon substituents also may be a single aromatic ring occupying all three of the nitrogen valences as illustrated in the case of pyridine.

Since the cationic portion of the quaternary ammonium germicides contemplated in this invention is considered the active component, the salt-forming anionic radical X is not generally regarded as being critical in nature. Any anionic radicals capable of yielding water-soluble salts can be used. Examples of such anionic radicals are the halides, sulfates, phosphates, carbonates, nitrite, alkyl sulphates, alkyl phosphates, formate, acetate, tartrate, and the like. Halide radicals such as chloride and bromide are particularly suitable with the chloride being preferred. Where the anionic portion of the quaternary ammonium germicide molecule is an alkyl sulfate, short-chain alkyl sulfates, in particular, are contemplated, such as methylsulfate, ethylsulfate, propylsulfate, etc.

The compounds can be prepared in several different ways, all of which will be apparent to one skilled in the art from my disclosure. For example, the long-chain alkylarylmethyl quaternary ammonium germicides can be suitably prepared by chloromethylation of a long-chain alkylarylmethyl compound to produce an alkylarylmethyl chloride which can then be condensed with any suitable tertiary amine to give the desired product. Halogenated long-chain alkylarylmethyl quaternary ammonium compounds on the other hand are conveniently prepared by direct halogenation of a long-chain alkylarylmethyl compound having from 1 to 4 methyl radicals attached to the aryl nucleus. When the halogenation is carried out in the absence of any halogenation catalyst which might promote substitution of the rings, a product is derived containing halogen in the long-chain alkyl radical as well as in one of the methyl radicals substituted on the aryl nucleus. This compound which may be denominated a halogenated alkylarylmethyl chloride can then be condensed with any suitable tertiary amine as in the preceding example to give the desired halogenated long-chain alkylarylmethyl quaternary ammonium compound.

Examples of the preferred long-chain alkylarylmethyl quaternary ammonium germicides coming within the scope of the above formula according to my invention are: octylbenzyl trimethyl ammonium chloride, nonylnaphthyl trimethyl ammonium chloride, dodecylbenzyl pyridinium chloride, dodecylbenzyl trimethyl ammonium bromide, dodecylmethylbenzyl trimethyl ammonium chloride, cetylbenzyl trimethyl ammonium methosulfate, octylbenzylphenyl-

triethyl ammonium nitrate, octadecylbenzyl trimethyl ammonium chloride, and the like.

The pine oil utilized in the long-chain alkyl-aryl quaternary ammonium germicide and pine oil compositions according to my invention is available in a number of different forms. It has been defined as being an oil obtained by steam distillation of the oleoresin from *Pinus palustris* Miller and certain other species of pine (Merck Index, 5th Ed., 1940). Pine oil as it is contemplated herein usually boils above about 200-220° C. and has a specific gravity of about 0.9. Although it is sometimes used as a disinfectant by itself, it has only mild germicidal properties as illustrated by its maximum effective dilution against *T. rosaceum* of about 1:30 compared to 1:80 for phenol.

Various mixtures of quaternary ammonium germicides and pine oil were prepared for testing to illustrate the proportional limits within which the germicidal activity of the quaternary ammonium germicide and pine oil composition exceeds that of both the pine oil and the quaternary ammonium compound. Such mixtures were prepared by placing the quaternary ammonium germicide in a vessel and adding pine oil, following which the ingredients were intimately mixed to produce the new and greatly improved germicidal compositions of this invention. The efficacy of the different compositions containing various proportions of a representative quaternary and pine oil is illustrated by the results of the tests which are set out in the following table:

TABLE

Fungicidal activity of quaternary ammonium germicide and pine oil compositions toward Trichophyton rosaceum

Quaternary Ammonium Compound Tested	Proportions, Percent by Weight		Maximum Effective Killing Dilution in Water
	Quaternary	Pine Oil	
Dodecylbenzyl Trimethyl Ammonium Chloride	0	100	1:30
Do	28.6	71.4	1:1000
Do	33.3	66.7	1:1330
Do	40.0	60.0	1:1600
Do	52.2	47.8	1:2630
Do	59.3	40.7	1:2960
Do	63.5	36.5	1:3080
Do	68.6	31.4	1:3463
Do	73.5	26.5	1:3340
Do	89.8	10.2	1:1800
Do	100	0	1:1500
Lauryl Dimethyl Benzyl Ammonium Chloride	50	50	1:1500
Chlorinated Dodecylbenzyl trimethyl ammonium chloride (approx. 5 chlorine atoms)	11.0	89.0	1:430
Do	12.4	87.6	1:500
Do	16.7	83.3	1:667
Do	100	0	1:600

The values for germicidal activity set out in the above table were obtained by determining the maximum effective killing dilution when mixed with water of different compositions prepared according to this invention as well as of the pure quaternary ammonium germicide and pine oil ingredients. The "maximum effective dilution" illustrates the killing power of the different compositions against a representative fungus such as *Trichophyton rosaceum* and was obtained by the testing method set out in Navy Department Specification 51D6. The higher the effective dilution, the greater the germicidal power of the composition tested.

From the above table of results and reference to the curve in the accompanying drawing which

was obtained by plotting the maximum effective dilution against the various proportions of quaternary and pine oil, the unexpectedly high germicidal activity of compositions according to my invention is readily apparent. It can be seen that my germicidal compositions containing substantial proportions of quaternary ammonium germicides and less than about 70% by weight of pine oil are decidedly superior to either pine oil or the quaternary ammonium compound in germicidal efficiency. Furthermore, any lowering of germicidal activity which would ordinarily be expected when a strongly germicidal material is diluted with a very mild germicide such as pine oil is surprisingly absent when the proportions according to the teaching of my invention are utilized.

Because of their higher germicidal activity, my novel compositions are more efficacious than either quaternary ammonium germicides or pine oil alone as well as compositions of pine oil fortified with only a small amount of quaternary ammonium germicide. Their greater efficacy renders them extraordinarily useful in the control of microorganisms, particularly spore-forming bacteria, fungi, and the like. Such uses include the disinfection of utensils and equipment used in drinking, eating and the preparation of foods, etc. Wearing apparel, bedding, upholstery, and the like, can also be effectively sterilized by the use of my germicidal compositions. Floors, walls, as well as various equipment such as lavatories, toilets, etc. in areas where it is desirable to promote germ-free surroundings can be conveniently disinfected with these germicidal compositions because of their greater germicidal activity. Other applications such as their use as antiseptic ingredients in germicidal detergents, ointments, cosmetics, etc. are also indicated.

The germicidal compositions, according to my invention, may contain various dyes or coloring agents which are compatible with the quaternary ammonium germicide and the pine oil in order to improve the general appearance of the compositions. The use of various perfumes and odor-masking agents is also contemplated.

In some instances, the germicidal compositions of this invention may contain water as, for example, when a composition is prepared by adding pine oil to an aqueous solution of the quaternary ammonium germicide. In the presence of certain amounts of water as, for example, amounts exceeding about 30% and less than about 90% by weight of the aqueous quaternary ammonium germicide and pine oil solution, a separation of the pine oil and aqueous quaternary ammonium germicide mixture may occur. Although such separation has no effect on the germicidal activity of my compositions, it will be preferred to maintain the water in amounts of less than about 30% and more than about 90% by weight whenever clear and completely miscible or homogeneous mixtures are desired for the sake of appearances.

The foregoing description and examples of the germicidal compositions according to my invention are intended as illustrative only. Many obvious variations and modifications of the invention will be apparent to those skilled in the art. All such variations and modifications as come within the scope of the appended claims are contemplated by my invention.

I claim:

1. A germicidal composition which comprises

from 40 to 90% by weight of an N-alkylbenzyl-N,N,N-trialkyl quaternary ammonium chloride and from 10 to 60% by weight of pine oil, said alkyl group on the benzyl nucleus containing from 8 to 18 carbon atoms and said nitrogen alkyl substituents containing no more than a total of 12 carbon atoms.

2. A germicidal composition which comprises from 40 to 90% by weight of an N-alkylbenzyl-N,N,N-trialkyl quaternary ammonium chloride and from 10 to 60% by weight of pine oil, said alkyl group on the benzyl nucleus being a propylene polymer containing from 12 to 15 carbon atoms and said nitrogen alkyl substituents containing no more than a total of 12 carbon atoms.

3. A germicidal composition which comprises 10 to 60% by weight of pine oil and 40 to 90% by weight of dodecyl benzyl trimethyl ammonium chloride.

RICHARD D. STAYNER. 20
